Attorney.

UNITED STATES PATENT OFFICE.

ALFRED G. SCHMIDT, OF BALTIMORE, MARYLAND, ASSIGNOR, BY MESNE ASSIGNMENTS, TO U. S. INDUSTRIAL ALCOHOL CO., A CORPORATION OF WEST VIRGINIA.

FAUCET.

Application filed March 25, 1922. Serial No. 546,937.

To all whom it may concern:

Be it known that I, ALFRED G. SCHMIDT, a citizen of the United States, residing at Baltimore city, State of Maryland, have invented 5 certain new and useful Improvements in Faucets, of which the following is a specification.

This invention relates to faucets, and more specifically to an improved faucet or 10 spigot or the like which has its valve operable by movement of its nozzle with relation to the tank-attaching body.

The main object of this invention is to provide simple and practical means for automatically closing the outlet of the tank-attaching body when the usual valve-closer is being repaired or replaced; that is, when the nozzle is removed for gaining access to the lower valve-closer.

20 Another object is to provide simple and effective means for retaining the upper or emergency valve-closer out of the valve-closing position when the nozzle is in place on the tank-attaching body.

25 Other objects and advantages will be pointed out or implied in the following details of description, in connection with the accompanying drawings in which—

Fig. 1 is a sectional view illustrating my 30 improvement applied to a faucet or spigot of the type shown in the Patent No. 453,668, patented June 9th, 1891.

Fig. 2 is a view similar to Fig. 1, but showing a modified form of the invention.

35 Fig. 3 is a view similar to Fig. 1, but showing another modified form of the invention, the lower section being omitted.

Fig. 4 is a view similar to Fig. 1, but showing another form of the invention, the 40 lower section being removed.

Fig. 5 is a horizontal sectional view, the section being along the line 5—5 of Fig. 3.

Fig. 6 is a horizontal sectional view, the section being along the line 6—6 of Fig. 4.

45 Fig. 7 is a horizontal sectional view taken along the line 7—7 of Fig. 4.

Fig. 8 is a view similar to Figs. 1 and 2 but embodying modifications.

Fig. 9 is a horizontal sectional view of 50 Fig. 8 through the member 15^b.

Fig. 10 is a view, in vertical section, of another form of the invention.

Fig. 11 is a bottom plan view of the valve-seat of the form shown in Fig. 10.

55 Referring to these drawings in detail, in

which similar reference characters refer to similar parts throughout the several views; the invention consists in the construction and arrangement or combination of parts which will be described in detail as follows:

The tank-attaching body may either be provided with the threaded connection for attaching it to a tank or the like, as shown in Fig. 1, or with any appropriate tank-attaching element. This body is provided with a valve-seat 2 which is a double valve-seat; that is, it is composed of an upwardly facing valve-seat and a downwardly facing valve-seat. This is true in all forms of the invention. The body 1 (of Figs. 1 and 2) is formed with upper and lower openings 3 and 4 which are above and below the valve-seat 2, respectively; and this body is formed with a screw-thread 5 around the lower opening, also a screw-thread 6 around the upper opening. According to the form shown in Fig. 3, the body 1^a (Fig. 3) is formed with upright parallel ribs or guides 7 for a purpose which will presently appear.

In all forms of the invention, the nozzle 8 has its upper end internally threaded for adjustably meshing with the threads 5, and a handle (9, 9^a, or 9^b) may be united with the nozzle or outlet-member by any appropriate means. A valve-closer 10 is removably seated on a closer-seat (11, 11^a, 11^b or 11^c), and the latter may be seated on a shelf 12 (Figs. 1, 4 and 8), or formed integrally with the nozzle as shown in Fig. 2. By turning the handle, so as to screw the nozzle up or down on the threads 5, the valve-closer (disk or washer 10) is moved against or away from the valve-seat 2. A stud or stop (13, 13^a or 13^b) may be provided on the handle 9 for limiting the handle's rotary movement with the nozzle. The handle may include a ring 13^a which is removably secured to the nozzle, also adjustable on the nozzle for properly adjusting the valve-closer with relation to the valve-seat.

The parts thus far described are not broadly claimed as new, except the upper opening 3, the threads 6 and the ribs 7, and except the valve-seat 2 (2^a in Fig. 4) being a double valve-seat which faces in opposite directions or both up and down. For cooperation with the upwardly facing side of the valve-seat, I provide an emergency valve-closer (shown at 14 in Figs. 1, 3, 8, and 10, at 14^a in Fig. 2; and at 14^b in Fig. 4). The

ribs 7 of Fig. 3 confine and guide the ball or valve-closer; that is, they form a cage for guiding the valve-closer to and from the valve-seat 2; but other means may be provided for confining and guiding the valve-closer, as shown at 15, 15^a, 15^b, and 15^c, respectively, in the different forms of the invention. In Figs. 1, 2, 4 and 10, the means for guiding the emergency valve-closer is wholly or partly united with a plug or closer 16 (16^a in Fig. 8, and 16^{aa} in Fig. 10) on which the usual porcelain index 17 is seated and secured by cement, a lock-nut (as indicated) or by any appropriate means. The plugs 16 and 16^a are preferably screwed into the upper opening 3 so as to be removable for access to the upper face of the valve-seat 2, also for removing and replacing or renewing the upper valve-closer. This upper opening also permits of conveniently and properly finishing the upper valve-seat in the process of manufacturing. Moreover, it permits of the valve-closer being properly and conveniently placed in the tank-attaching body. This upper opening also provides for access to the guides 7, for planing or otherwise finishing them (Fig. 3), or for inserting the valve-guiding means of Figs. 1, 2, 4, 8 and 10. It also permits insertion of the member 15^b (Fig. 8) which is a combined cage, valve-guide and oppositely facing or duplex valve seat.

In Fig. 10, slots 5 may be provided in the plug-seat, so the flange of the valve 2 can be passed therethrough to the threaded seat, for this valve-seat, in the body 1^P.

In Fig. 4, the body 1^B is formed with a valve seat of slightly different form from the other valve-seats.

In Figs. 8 and 10, the valve seats are primarily separate and are insertable through the upper openings of the respective bodies 1^c and 1^P.

Washers or other suitable packing may be provided where indicated or wherever needed.

In each form of the invention, means is provided to hold the upper or emergency valve-closer spaced from the valve-seat when the faucet is in its usual or working condition, this means permitting the emergency valve to automatically move to valve-closing position, on the seat 2, when the nozzle is removed from the tank-attaching body; and in each form except that of Fig. 4, this valve-controlling means is supported by the nozzle and extends up through the opening of the valve-seat, as indicated at 18; but in Fig. 4, the valve-closer carries a depending stud 18^a which extends down through the valve-opening and usually rests on the lower valve-seat or valve-closer.

From the foregoing it will be seen that

when the nozzle is raised, its lower valve-member closes the valve, and that when the nozzle is removed, the emergency valve-closer closes the valve, operating automatically as soon as permitted to do so by the lowering of the controlling stud or post 18 or 18^a.

It is not intended to limit this invention to the exact details of construction here shown and described, but changes may be made within the scope of the inventive ideas as implied and claimed.

What I claim as my invention is:

1. A faucet having a median partition provided with upper and lower valve-seats adjacent to upper and lower valve chambers, a rotatable nozzle having therein a valve-closer adapted to seat against the lower valve-seat, a valve guided to seat against the upper valve-seat, and a removable plug in the faucet having a guide for the valve projecting into the upper valve chamber.

2. A faucet having a median partition provided with upper and lower valve-seats adjacent to upper and lower valve chambers, a rotatable nozzle having therein a valve-closer adapted to seat against the lower valve-seat, a valve guided to seat against the upper valve-seat when the nozzle and its closer are removed, and a removable plug in the faucet having a guide for the valve projecting into the upper valve chamber.

3. A faucet having a median partition provided with upper and lower valve-seats, a rotatable nozzle having therein a valve-closer adapted to seat against the lower valve-seat, a rotatable handle associated with the nozzle and adjustable thereon, a valve guided to seat against the upper valve-seat and a removable plug in the faucet above the valve to gain access thereto.

4. A faucet provided with upper and lower valve-seats adjacent to upper and lower valve-chambers, a rotatable nozzle having therein a valve-closer adapted to seat against the lower valve seat, a valve guided to seat against the upper valve-seat, a removable plug in the faucet, and a guide for the last mentioned valve, said guide being located in the upper valve-chamber.

5. A vertically disposed faucet having a median partition provided with upper and lower valve-seats, a valve-chamber above the partition and a horizontally disposed liquid conduit connected to the valve-chamber, a valve in the chamber normally disposed considerably above its seat to present no obstruction to the flow of liquid, and a rotatable nozzle having therein a valve-closer adapted to seat against the lower valve seat.

In testimony whereof I affix my signature.

ALFRED G. SCHMIDT.
